UNITED STATES PATENT OFFICE

2,090,762

SASH OR STORE FRONT CONSTRUCTION

Clyde Dean Lowry, Lincoln, Nebr., assignor to
Libbey-Owens-Ford Glass Company, Toledo,
Ohio, a corporation of Ohio

Application February 5, 1934, Serial No. 709,889

27 Claims. (CL 20—56.4)

The present invention relates to sash or store front construction and embodies improved front and rear sections or strips combined, co-operating and tensioned in a novel manner to clamp and hold the glass pane of the sash or store front.

My improvements may be embodied in a sash or front wherein the front and rear sections or strips are solely of relatively stiff heavy extruded metal, or, wherein these sections or strips are of relatively thin gauge drawn or rolled moulding combined with, and bodily carrying, relatively stiff clips whose mounting and tensioning holds the mouldings in pane-clamping position.

My invention embodies a knife-edge fulcrum on one of the sections or clips, as the case may be, bearing on, or contacting, a seat on the other section or clip.

Preferably, the seat is the junction of conveying parts or surfaces which define a sharp groove that "centers" the knife-edge fulcrum.

The knife-edge fulcrum and its seat permit the tensionable or so-called movable, or clamping, section to be adjusted by the tensioning means, such as a screw carried by the rear section, with facility and yet without displacement of the movable section from the knife-edge fulcrum.

I prefer, however, to provide a guard-lock which prevents displacement of the movable section from its knife-edge fulcrum. This guard-lock comprises a projecting guard on one section received freely within a slot or groove in the other section, the projecting guard and the slot preferably lying in the arc of a circle whose center is the edge of the knife-edge fulcrum.

In lieu of a slot, the guard-lock may comprise merely two overlapping parts, preferably curved, or having curved surfaces, arranged to prevent the knife-edge fulcrum from becoming displaced.

Once the front and rear sections are fulcrumed and tensioned to hold the pane they are, in a sense, interlocked although the guard-lock parts or members are not designed to contact with each other. The movable section is thus prevented from being displaced or pried off by unauthorized persons.

To facilitate the hinging and un-hinging of the front section, it may be provided with a supplemental seat for the knife-edge fulcrum for setting or removal of said section, said two seats being successively used in assembly or disassembly.

When the improvements are embodied in a division, corner, or reverse bar the movable sections may be joined by flexible means such as drawn spring clips, making them unitary and

enabling them to relatively flex in either direction for ease in handling, and when installing the construction.

My invention also embodies a new resilient automatic brake which prevents the application of too great pressure by the tensioning means, said brake being susceptible of modification and usable in a construction having my improved knife-edge fulcrum and guard-lock, or in other constructions.

The improvements may be used in connection with fixed or sliding sash, or a casement window or transom which is hinged, or a store front.

The invention may be utilized in other forms than those herein disclosed without departing from its essential principles.

In the accompanying drawings:

Figure 1 is a fragmentary sectional assembled view of one embodiment of the invention applied to a casement window, where the parts are of heavy extruded metal;

Fig. 2 is a similar view of a modification having rolled or drawn mouldings provided with extruded clips, the sections being shown in separated relationship;

Fig. 3 is a view like Fig. 1 showing a modification adapted for calking;

Fig. 4 is a view like Fig. 3, showing another modification;

Fig. 5 is a view like Fig. 2, illustrating the use of extruded clips carried by front and rear rolled or drawn mouldings corresponding to the form shown in Fig. 4;

Fig. 6 is a fragmentary sectional view of another modification showing how the invention may employ a different tensioning device adjustable from the front and, also, be used either in a single or double glazed installation;

Fig. 7 is a fragmentary sectional view of a division bar embodying the invention and illustrating how the improvements may be incorporated in corner or reverse bars;

Fig. 8 is a fragmentary view showing how the embodiment of Fig. 7 may be carried out by the use of extruded clips carried by rolled or moulded sections;

Fig. 9 is a view like Fig. 7 showing a modification of division, corner, or reverse bar wherein the clamping sections are connected together by spring clips which flex both ways;

Figs. 10 and 11 are views of modifications employing, in addition to features shown in preceding figures, resilient arms or flanges and automatic braking devices which prevent excessive pressure on the pane; and

Fig. 12 is a view of a modification including a resilient arm or flange and a rigid arm which indicates to the installer when the tension is sufficient.

5 Referring first to Fig. 1, the rear or back section is shown at 1 and the front or outer adjustable section at 2, these being of heavy extruded metal.

In this embodiment, the sections 1 and 2 are 10 supported by a casement or sash 3, to which section 1 is hinged at 4 in any suitable manner, showing how the invention may be used in connection with casements and transoms. The casement or sash may have drainage openings 5.

15 The rear section 1 is extended forwardly at 6, thence upwardly as at 7 which part has a knife-edge fulcrum 8 extending the entire length of the part 7 and serving as the sole support and hinging or fulcruming means for the front or 20 outer section 2.

The knife-edge fulcrum 8 is a sharp ridge, as distinguished from knuckle-like, curved, or rounded fulcrums such as have heretofore been proposed for the rockable mounting of adjustable 25 front or outer sections for sash or store fronts.

My knife-edge fulcrum 8 is seated in a valley-like seat or bearing 9 on the underside of section 2, said seat being defined by converging surfaces on the said section.

30 Reference being had to the different embodiments of the invention shown in the drawings, particularly those of Figs. 1 to 6, it will be seen that where the section 2 is of extruded material, the seat or bearing 9 is defined by converging surfaces on the body of the section 2 and on an arm or flange carried thereby, and where extruded clips are used in connection with rolled or drawn mouldings, the seat is provided at the convergence of surfaces on the body and arm thereof; further, that the arm or flange is the part or member through which the tensioning action is exerted on the front section as, for instance, by screw action.

In Fig. 1 the arm or flange appears at 10 and 45 is subject to the pressure-tensioning action of a screw 11 which engages a screw threaded hole 12 in the section 1, there being provided as many screws 11 and holes 12 at different points of the length of the section 1 as necessary to effect even 50 and suitable tensioning of the sections 1 and 2 on the pane 13.

In the construction shown in Fig. 1, the arm or flange has a second or auxiliary seat 14 corresponding to seat 9 and adapted to receive knife-edge fulcrum 8 during the act of assembly or disassembly of the section 2 with section 1, as will presently appear.

The upstanding part 7 is provided with a curved overhanging surface 15 under which a curved 60 flange 16 on section 2 is adapted to lie. Preferably, the curved parts 15, 16 lie in arcs of circles struck from the knife-edge fulcrum 8 as a center. The parts 15, 16, constitute a guard-lock which prevents accidental disengagement of the fulcrum 8 from its seat 9 or the prying off of the section 2.

65 It will be understood that it is not intended that the parts 15, 16 engage while the sections 1 and 2 are in their tensioned condition as shown in Fig. 1. If, however, attempt is made by an unauthorized person to pry off the section 2 from fulcrum 8, such action will be prevented by the guard-lock 15, 16. Furthermore, the parts 15, 16 also serve the purpose of keeping the section 2 in its proper position during the assembly until 70 the screws 11 are tightened but once the section

2 is properly tensioned, the tension maintains it on its fulcrum 8 without requiring engagement of parts 15, 16.

The pane may rest on metal or wooden blocks or a strip 17, as is customary.

When disassembling the sections 1 and 2, the screws 11 are loosened to free the arm or flange 10, the part 16 pushed under part 15 and the upper pane-engaging part pulled out, which will enable the auxiliary seat 14 to receive knife-edge fulcrum 8. The top of section 2 is then pushed in which will free part 16 from part 15, whereupon the section 2 may be lifted off the fulcrum 8 and detached from section 1. A reversal of these steps will enable the section 2 to be assembled with section 1, the seat 14 first being made to receive the fulcrum 8 and reverse-order operations before described will complete the assembly, whereupon the screws 11 are tightened to tension the front section 2 on pane 13.

The construction disclosed in Fig. 2 is, in principle, like that shown in Fig. 1, except that the sections 1 and 2 are of rolled or drawn metal and bodily carry extruded clips 18 and 19, respectively, at intervals of their lengths. The clip 18 has a seat 9 and an arm 10 provided with a supplemental seat 14. The part 16 of the guard-lock which corresponds to the part 16 of Fig. 1 comprises the bent, freely projecting lower edge of section 2 and projects under the part 15 of the upstanding forward end of extruded clip 19.

The knife-edge 8 at the top of part 7 is adapted to bear on seat 9 of clip 18 and to be used in connection with seat 14 when assembling or disassembling the sections 1 and 2, as described in connection with Fig. 1.

The clips 18 and 19 are held by the bent ends of the sections 1 and 2 as shown at 20, 21, 22, 23 and additional thereto, the section 1 is re-bent to provide a gutter 24. Screws, such as shown at 25 40 41 are used in Fig. 2 to co-operate with the arm 10 for tensioning purposes, as previously described in connection with Fig. 1. Drainage openings such as shown at 5 may be provided at suitable points.

In the construction shown in Fig. 3, the sections 1 and 2 are of extruded metal and embody the principle of the construction shown in Fig. 1, though in different form. The rear section 1 has an integral gutter 25, a base 6 which is provided with longitudinally extending weather-proof packing-receiving grooves 26 on its bottom, and an upstanding part 7 provided with a knife-edge fulcrum 8 adapted to engage a seat 9 on section 2.

The upstanding part 7 is provided at its front with a channel 27 which receives the lower part of the front section 2, said lower part in this form being of double construction. The arm or flange 10 which constitutes a part of the section 2, is provided with a curved part 16, as in Figs. 1 and 2, which constitutes a part of the guard-lock whose other part is an arc-shaped channel or slot in the upstanding part 7, the upper wall 15 of said slot serving the purpose of the walls 15 of Figs. 1 and 2. Screws 11 which are carried by the rear section 1, bear on the flange or arm 10 and provide for applying the desired tension to the front section, as previously described.

70 Drainage openings (not shown) may be provided for the gutters 24 and 25 as well as at 5, as customary in sash and store front constructions.

In Fig. 4, the construction corresponds to that

of Fig. 3 except that the lower part of the front section 2 is solid instead of double, as in Fig. 3.

The construction illustrated in Fig. 5 represents the same changes over that of Fig. 4 as does the construction of Fig. 2 to that of Fig. 1. The sections 1 and 2 are of rolled or drawn metal and bodily carry extruded clips 28, 29, respectively held by the bent parts 30, 31, 32, 33 of said sections 2 and 1. A gutter 34 is provided on section 1. The screw hole 12 receives the tensioning screw 11 whose tip is adapted to bear on the arm of flange 10 of clip 28.

In Fig. 6, there is shown an embodiment for either single or double glazed sash embodying the principle heretofore described, and particularly as shown in Figs. 3 and 4, but with a modified tensioning means comprising screws 11 that engage threaded holes 35 in metal blocks or pieces 36 which, on tightening the screws 11, effect tension on the arms or flanges 10. While the adaptation of the improvements to a double glazed sash having a common backstop 37 corresponding to section 1, is shown in Fig. 6, it will be understood that the tensioning means illustrated 25 may be used in connection with a single glazed sash. As shown, the backstop 37 is integral with the other parts of section 1 and serves in the place of two such sections 1, the construction taking the place of two independent installations 30 where double glazing is to be used.

In the embodiments of Figs. 2, 3, 4, 5, 6, as in that of Fig. 1, the surfaces 15 are struck in the arc of a circle whose center lies in the knife-edge 8 and, ordinarily, there is no contact between the surface 15 and the upper surface of the part 16 when the section 2 has been set and tensioned to hold the pane.

In Fig. 7 there is shown an embodiment of the invention in a division bar. The same principle 40 may be used in a corner or reverse bar by employing clamping sections whose angular construction adapts them thereto.

The panes are engaged on their outer faces by an extruded division bar 38 having integral 45 therewith two upstanding parts 7 each having a knife-edge fulcrum 8, corresponding to parts previously described. The two extruded clamping sections 39 have seats 9 to engage the respective knife-edge fulcrums 8 and at their outer 50 parts they bear on the inner faces of the panes 13.

The panes are clamped between the bar 38 and the sections 39 by screw tensioning means, of which one example is shown, embodying a screw 40 whose head is connected to the bar 38 at 41 55 and whose stem is engaged by nuts 42 and 43 with an extruded back channel tensioning bar which is surmounted by a tubular bar 45 bearing thereon.

The bar 44 has knife-edge fulcrums 46 which 60 engage angle or valley-like seats 47 on the clamping sections 39.

In Fig. 8 there is illustrated (as in Figs. 2 and 5), a modification of the construction shown in Fig. 7, wherein the division bar 38 may be of 65 rolled or drawn metal carrying extruded clips 48 at suitable intervals of its length, and the clamping sections 39 being provided with extruded clips 49 at suitable intervals of their length, said sections and clips corresponding in shape and 70 functions to the bar 38 and sections 39. The clips 48, 49 are held by suitably formed parts of the bar 38 and section 39 as at 50 and 51.

In Fig. 9, the construction is similar to that disclosed in Fig. 7 but as an additional improvement, the clamping sections 39 are connected by

spring clips 52 secured to, and connecting the clamping sections 39 in such manner that said sections 39 may flex in relation to each other in both directions. This feature facilitates the handling of the clamping sections 39 during assembly 5 and installation of the construction. The clips may be secured to the sections 39 in any desired manner. As shown, the sections 39 are provided with channels 53 into which the bent ends of the clips are sprung, fitted or fastened.

In Figs. 10 and 11, the construction embodies the principle disclosed in the construction of Fig. 1, and other figures previously described, carried out by a reversal of the arrangement of the knife-edge fulcrum and guard-lock, with the addition of an automatic brake which prevents too great tension being applied to the pane, guards against breakage of the pane, and insures even pressure along the face of the glass.

Referring first to Fig. 10, the flange or arm, instead of being a rigid part of the outer adjustable section 2, comprises a leaf spring arm 54 suitably secured to section 2 as at 55 and being bodily carried by, and projecting from, the section 2 as does the arm or flange 10 and tensioned by a screw 11 on section 1, the latter having a gutter 56, if desired.

The section 2 has a knife-edge fulcrum 57 on its lower part which rests in a seat 58 of the character of seat 9 but the seat 58 is carried by the forward part of section 1 instead of by the section 2. It will be observed that the fulcrumming action is the same in principle as heretofore but the arrangement is reversed.

The guard-lock feature previously described is carried out by the provision of the curved parts 15, 16, as heretofore, and, in addition, there are overlapping flanges 59, 59' on sections 2 and 1, respectively, which guard or protect the fulcrum 57 against weather conditions, the use of instruments by unauthorized persons who may seek to pry off the section 2, and for other purposes.

The opposing faces 60, 61', which are preferably curved and lie in arcs of circles whose center is the knife-edge fulcrum 57, are adapted to contact each other when the screw 11 has been tensioned beyond the requisite extent to enable the section 2 to properly hold the pane 13. When this has been done, an automatic braking action occurs at the surfaces 60, 61', preventing further pressure from being exerted on the pane even though the screw 11 be screwed up tighter. This braking action prevents injury to the pane though not interfering with the adaptability of the section 2 to yield sufficiently to compensate for any vibration to which the pane may be subject.

The surfaces 15, 16 may be tapered or provided with any friction facing, if desired.

The construction shown in Fig. 11 is substantially that of Fig. 4 modified to include a leaf spring arm 61 whose nature and object is that of leaf spring arm 54 but adapted to the particular arrangement of upstanding knife-edge fulcrum 7 and parts 15, 16 illustrated in Fig. 4. The leaf spring arm 61 being shaped very much like the arm of Fig. 4 and co-operating with the parts in the manner shown in Fig. 4, also has the added function of being forced against the surface 60 to exert an automatic braking action thereon should the screw 11 be screwed up too tight. This construction has all of the advantages of the one shown in Fig. 10, as previously described.

In Fig. 12, the construction disclosed, embodying a leaf spring 62 suitably secured to section 2 at 55, is a supplemental means which receives

the pressure from screw 11 and, up to a certain extent of tensioning by said screw, enables the section 2 to yieldingly engage the pane, as with the constructions of Figs. 10 and 11. The section 5 2 being provided with a rigid arm or flange 63 integral therewith or fastened thereto, when the screw 11 is screwed up far enough, it will force the leaf spring 62 against the arm or flange 63 which will, by the added resistance, advise the 10 person making the installation that the tension is sufficient.

The flexible tensioning means, automatic braking means, and other features may be embodied in other installations of sash and store fronts 15 and are not necessarily limited to use in connection with the knife-edge fulcrum and guard-lock features although particularly well adapted for combination therewith, as will be apparent.

What I claim is:

20 1. In a sash or store front construction, the combination with pane-holding sections, of a fulcrum on one section, two fulcrum seats on the other section for use at different times by said fulcrum during assembly and disassembly of said 25 sections, and tensioning means for said sections.

2. In a sash or store front construction, the combination with pane-holding sections, of a fulcrum on one section, two fulcrum seats on the other section for use at different times by said 30 fulcrum, means for tensioning said sections, and a guard-lock which prevents displacement of the aforesaid fulcrum from its seat when the sections are under tension by said tensioning means.

3. In a sash or store front construction, the combination with pane-holding sections, of fulcrum means for said sections, and tensioning means comprising, in part, a flexible member co-operating with said sections, adapted to exert an automatic braking action to prevent excessive 40 tension and, in part, means for exerting tension on said flexible member.

4. In a sash or store front construction, the combination with pane-holding sections, of fulcrum means for said sections, and tensioning 45 means comprising, in part, an outstanding resilient member carried by one of said sections and, in part, means carried by the other of said sections, the latter means being engageable with said resilient member to place said member under tension, said resilient member effecting an automatic braking action to prevent excessive tension being put on the pane.

5. In a sash or store front construction, the combination with pane-holding sections, of fulcrum means for said sections, a guard-lock to maintain the fulcrum in operative condition, a resilient member through which tension may be applied to said sections to hold the pane, means for tensioning said resilient member, and an automatic brake which is brought into action by said resilient member to prevent excessive tension being put on the pane.

6. In a sash or store front construction, the combination with relatively movable pane-holding sections, of tensioning means for said sections, and a brake which is automatically applied to prevent excessive tension.

7. In a sash or store front construction, the combination with relatively movable pane-holding sections, of tensioning means for said sections, including a resilient member which is subject to tension, and a brake which is automatically applied by said resilient member to prevent excessive tension on said member.

75 8. In a sash or store front construction, the

combination with relatively movable pane-holding sections, of a tensioning device carried by one of said sections, a resilient member carried by the other section which is subject to the action of said tensioning device, and a brake which is carried by the resilient member and is automatically applied to one of the sections to prevent excessive tensioning.

9. In a sash or store front construction, the combination of pane-holding sections, one section having a supplemental flexible means, and means extending from the other section for exerting pressure upon said supplemental means for indicating when sufficient tension has been applied.

10 10. In a sash or store front construction, the combination with relatively movable pane-holding sections, of a leaf spring connected with one section and a screw connected with the other section 15 for exerting tension upon the spring, the spring serving to advise the operator when the tension exerted by the screw is sufficient.

11. In a sash or store front construction, the combination of two pane holding sections constructed and adapted to embrace the window pane on opposite surfaces, the two sections being hingedly but detachably connected together, the sections having concentric curved parts constructed from the hinge as a center, said parts constituting a guard lock located at the outer side of the window pane, and adjustable means extending from one section to the other for creating outward pressure on each at points away from the window pane whereby the portions of the sections contacting the opposite surfaces of the window pane are forced securely in contact with the latter.

12. In a sash or store front construction, the combination with pane-holding sections one of which is fulcrumed upon the other, of a guard-lock which prevents displacement of said section from the fulcrum, and tensioning means for said sections.

13. In a sash or store front construction, the combination with pane-holding sections one of which is fulcrumed upon the other, of a guard-lock which prevents displacement of said section from the fulcrum, and tensioning means for said sections, said guard-lock comprising parts carried by the respective sections which may interlock to prevent displacement of the section 45 fulcrumed upon the other and control the tensioning means for said sections.

14. In a sash or store front construction, the combination with pane-holding sections one of which is fulcrumed upon the other, of a guard-lock which prevents displacement of said section from the fulcrum comprising curved faces on the respective sections which lie in arcs struck from the fulcrum as a center and may interlock to prevent displacement of the section from the section upon which it is fulcrumed, and tensioning means for said sections.

15. In a sash or store front construction, the combination of a fixed and a movable pane-holding section adapted to receive and grip a pane of glass therebetween, adjustable tensioning means for effecting movement of the movable section toward the fixed section to grip said pane therebetween, and means constituting a positive stop for the tensioning means to prevent further forward movement thereof when said sections exert a substantially predetermined gripping pressure upon the pane.

16. In a sash or store front construction, the combination of a fixed and a movable pane-hold-

ing section adapted to receive and grip a pane of glass therebetween, adjusting means for effecting movement of the movable section toward the fixed section to grip said pane therebetween, and means disposed in the path of said adjusting means for preventing tightening movement thereof beyond a predetermined point irrespective of the thickness of pane being gripped.

17. In a sash or store front construction, the combination of a fixed pane-holding section, a movable pane-holding section pivotally associated with said fixed section, said sections being adapted to receive and grip a pane of glass therebetween, an adjusting element for effecting movement of the movable section toward the fixed section and into gripping engagement with the pane, and a fixed stop for limiting the movement of the adjusting element to prevent further movement of said movable section toward said fixed section.

20. 18. In a sash or store front construction, the combination of a fixed pane-holding section, a movable pane-holding section pivotally associated with said fixed section, said sections being adapted to receive and grip a pane of glass therebetween, tensioning means carried by the fixed section and engaging a portion of the movable section for moving the same toward said fixed section to grip the pane therebetween, and a fixed stop also on the fixed section for limiting the movement of the tensioning means irrespective of the thickness of pane being gripped to prevent excessive tension on said pane.

19. In a sash or store front construction, the combination of a fixed pane-holding section, a movable pane-holding section pivotally associated with said fixed section, said sections being adapted to receive and grip a pane of glass therebetween, adjustable tensioning means for the sections, resilient means acted upon by said tensioning means for transmitting the movement thereof to the movable section to urge said section into yielding engagement with the pane of glass, and a positive stop for the tensioning means to prevent further tightening thereof when the movable section exerts a substantially predetermined gripping pressure upon the pane.

20. In a sash or store front construction, the combination of a fixed pane-holding section, a movable pane-holding section pivotally associated with said fixed section, said sections being adapted to receive and grip a pane of glass therebetween, adjusting means carried by the fixed section, resilient means carried by the movable section and acted upon by said adjusting means for transmitting movement thereof to the movable section to urge it into yielding engagement with the pane of glass, and a fixed stop for limiting the movement of the adjusting means to prevent the amount of pressure exerted by the sections upon the pane of glass from exceeding a substantially predetermined maximum.

21. In a sash or store front construction, the combination of a fixed and a movable pane-holding section adapted to receive and grip a pane of glass therebetween, tensioning means for the sections including a rigid adjusting member and a resilient member associated with said sections, said resilient member being acted upon by the adjusting member to urge the sections into yielding engagement with the pane of glass, and means for limiting the movement of the resilient member to prevent excessive pressure from being applied by the sections to the pane irrespective of the thickness of said pane.

22. In a sash or store front construction, the combination of a fixed and a movable pane-holding section adapted to receive and grip a pane of glass therebetween, an adjusting member carried by one section, a spring member acted upon by the adjusting member to urge the sections into yielding engagement with the pane, and means for limiting movement of the adjusting member to prevent any further increase in the spring pressure when a substantially predetermined gripping pressure is applied by the sections to the pane.

23. In a sash or store front construction, the combination of a fixed and a movable pane-holding section adapted to receive and grip a pane of glass therebetween, tensioning means for said sections including cooperating rigid and resilient members associated with the sections for effecting relative movement thereof toward one another to grip the pane therebetween, and fixed means for limiting the movement of the rigid and resilient members to prevent further movement of the sections toward one another.

24. In a sash or store front construction, the combination of a fixed and a movable pane-holding section adapted to receive and grip a pane of glass therebetween, a resilient member carried by one of the sections, an adjusting member carried by the other section and when tightened acting upon the resilient member to build up a spring pressure for urging the movable pane-holding section into yielding engagement with the pane, and means for limiting the movement of the adjusting member to prevent the building up of any further spring pressure when the sections exert a substantially predetermined gripping pressure upon the pane of glass.

25. In a sash or store front construction, a fixed section and a movable section associated therewith and relatively movable with respect to said fixed section, the said fixed section including a base having a raised portion constituting a seat, and means for clamping a pane of glass between said sections including a spring arm fixed at one end to the movable section and having its opposite free end extending beneath the pane of glass toward the fixed section and spaced above said base, and a screw carried by the fixed section and engaging the free end of the spring arm for urging an intermediate portion of said arm into engagement with said seat.

26. In a sash or store front construction, a fixed section and a movable section associated therewith and relatively movable with respect to said fixed section, the fixed section including a base the forward end of which is provided with vertically spaced portions constituting an outwardly opening channel while the said movable section is provided adjacent its lower end with an inwardly directed portion freely received in said channel, and means for clamping a pane of glass between said sections including a spring element fixed at one end to the movable section and having its opposite free end extending beneath the pane of glass toward the fixed section, and a tensioning member carried by the fixed section and engaging the free end of said spring element.

27. In a sash or store front construction, a fixed section and a movable section associated therewith and relatively movable with respect to said fixed section, the fixed section including a base having a raised portion constituting a seat and the forward end of said base being provided with vertically spaced portions constituting an out-

wardly opening channel, while the said movable section is provided adjacent its lower end with an inwardly directed portion freely received in said channel, and means for clamping a pane of glass between said sections including a spring arm fixed at one end to the movable section and having its opposite free end extending beneath the

pane of glass toward the fixed section and spaced above said base, and a screw carried by the fixed section and engaging the free end of the spring arm for urging an intermediate portion of said arm into engagement with said seat. 5

CLYDE DEAN LOWRY.
